[57] **CLAIM**

The ornamental design for a toy vehicle, substantially as shown and described.

DESCRIPTION

FIG. 1 is a perspective view of a toy vehicle showing my new design;

FIG. 2 is a side elevational view thereof, the side opposite being substantially a mirror image thereof;

FIG. 3 is a top plan view thereof;

FIG. 4 is a front elevational view thereof;

FIG. 5 is a rear elevational view thereof;

FIG. 6 is a bottom plan view thereof; and

FIG. 7 is a perspective view of the toy vehicle which is similar to FIG. 1, but showing the vehicle in a slightly different condition.

FIG. 1

FIG. 2

FIG. 3

FIG. 4

FIG. 5

FIG. 6

FIG. 7
